UNITED STATES PATENT OFFICE.

CLARENCE D. PLATT, OF BRIDGEPORT, CONNECTICUT.

SWITCH-HANDLE.

1,805,158.

Specification of Letters Patent. Patented May 27, 1919.

Application filed April 27, 1918. Serial No. 231,241.

To all whom it may concern:

Be it known that I, CLARENCE D. PLATT, a citizen of the United States of America, residing at Bridgeport, Connecticut, have invented a new and useful Switch-Handle, of which the following is a specification.

My present invention relates particularly to knife switches and the objects of my invention have been to provide a practical and convenient form of handle for said switches which can be readily produced and can be readily secured to the switch blades.

Other objects are to provide a handle structure which will be strong and durable and which can be firmly fixed to the switch blades. Briefly, the invention consists of a switch handle arranged to connect the parallel blades of the switch, with attaching members having hooked engagement with the switch blades and screw devices engaged with said attaching members for drawing the handle into firm engagement with the switch blades. Preferably, the handle is recessed to receive the said attaching devices and the end portions of the switch blades, and the said attaching devices may be in the form of internally threaded bushings slotted in one side to provide the hooked portions for engagement with the switch blade.

Other features of the invention and details of construction will appear as the specification proceeds.

In the accompanying drawing, I have illustrated the invention embodied in one practical commercial form, but at the same time would have it understood that various modifications and changes may be made without departure from the true spirit and scope of the invention.

In this drawing:

Figure 1 is a top plan view of a switch having my improved handle applied thereto, the handle structure being broken away and shown in section at one end.

Fig. 2 is a longitudinal sectional view of the switch taken substantially on the plane of the line 2-2 of Fig. 1.

Fig. 3 is a broken detail view of one end of the handle.

Figs. 4 and 5 are sectional and front views respectively of the attaching bushing.

The switch illustrated is of the usual knife blade type embodying substantially parallel switch blades 7 pivoted at 8 on the hinge posts 9 and arranged to engage at their free ends with the contact clips 10, the hinge

posts and clips having suitable terminals such as the binding posts indicated at 11 and 12 and the whole being mounted on a suitable base 13.

The handle 14 may be made in any suitable shape, it being shown here as of "dumb bell" formation, having enlarged heads at its opposite ends, socketed at 15 to receive the ends of the switch blades. These handles are usually made of insulating material molded to the desired shape.

The enlarged heads provide ample cross section of material at the points in the handle where the perforations are made and these heads furthermore form guards tending to prevent contact of the fingers of the operator with live metal parts, as will be clear from Fig. 1.

The so-called attaching devices consist in the present disclosure of internally threaded bushings 16 received in sockets 17 provided therefor in the handle and slotted in one side thereof as indicated at 18 to provide hooks or hooked portions 19 on the ends 20 thereof for engagement in slots or openings 21 provided therefor in the ends of the switch blades.

Cooperating with the attaching members are suitable screw devices, taking the form 22 in the present disclosure of the screws 23 engaged in the internally threaded members 16 and having their head portions seated in recesses or pockets 24 provided in the outer side of the handle, said seats being connected by the passages 25 with the bushing recesses 17 in the opposite side of the handle.

In assembling the parts, the bushings are first hooked onto the ends of the switch blades and the handle is then slipped over said bushings, fitting down over said bushings and the end portions of the blades. The handle then serves to prevent lateral displacement and disengagement of the bushings from the switch blades. The screws are then inserted from the outer side of the handle into engagement with the threaded bushings and serve as they are tightened to draw the handle into firm engagement with the ends of the blades. This provides a rigidly supported handle which can be brought firmly into engagement with the switch blades so as to make up for inequalities in the size of the parts by the simple tightening of the screws. The parts are easily assembled as will be clear and provide a firm, strong handle construction which will not

- ordinarily become loosened but which, if it does become loosened, can readily be made firm with the switch blades. Another advantage of the invention resides in the fact 5 that the switch handle can be molded without any metal "inserts" such as have heretofore been common. This enables the handles being made at one point and the metal parts being made at another point, eliminating the 10 need for supplying the handle manufacturer with metal inserts to be placed in the handles at the time of manufacture.

I claim:-

1. In combination, a switch blade, a screw 15 threaded attaching member having a hooked portion engaged with said switch blade, a handle recessed to receive said attaching member and a portion of the edge of the switch blade and a securing screw extending 20 through a portion of the switch handle into engagement with the threaded attaching member.
2. A handle construction for knife switches comprising, in combination with parallel 25 switch blades, screw threaded attaching members having hooked connection with the end portions of said blades, a handle connecting the blades and recessed to fit over said attaching members and the end portions 30 of the blades, and screw threaded handle securing devices engaged with the threaded attaching members.

3. In combination with a switch handle, having recesses in one face to seat the end portions of parallel switch blades and recesses in the opposite face to receive the head portions of screw fastening devices, said recesses in the opposite faces being connected by transverse passages, switch blades having their end portions engaged in the seats aforesaid provided therefor, internally threaded bushings connected with the switch blades and extending into the transverse passages aforesaid, and securing screws engaged with said bushings and having their heads seated in the recesses provided therefor in the opposite side of the handle.

4. As an article of manufacture, switch handle securing means comprising, an externally smooth substantially cylindrical member having a deep slot cut in one side thereof to form an angular hook portion for engagement with a switch blade and said member further having a screw-threaded portion for engagement with a screw device.

5. As an article of manufacture, a switch handle securing device comprising, a length of tubing free of external projections, having screw threads on the interior thereof and having a relatively deep slot cut in one side thereof to provide an angular hook portion for engagement in an opening in a switch blade.

CLARENCE D. PLATT.
